DESIGN FOR A TOY ANIMAL FIGURE

Constance Ray White, Beverly Hills, Calif.

Application December 15, 1948, Serial No. 150,163

Term of patent 7 years

(Cl. D34—2)

To all whom it may concern:

Be it known that I, Constance Ray White, a citizen of the United States, residing at Beverly Hills, in the county of Los Angeles and State of California, have invented a new, original, and ornamental Design for a Toy Animal Figure, of which the following is a specification, reference being had to the accompanying drawing, forming part thereof.

In the drawing:

Fig. 1 is a front view of a toy animal figure, showing my new design;

Fig. 2 is a rear view, and

Fig. 3 is a side view thereof.

I claim:

The ornamental design for a toy animal figure, substantially as shown.

CONSTANCE RAY WHITE.
